UNITED STATES PATENT OFFICE.

JAMES ALISON McWILLIAMS, OF CHICAGO, ILLINOIS.

FOLDABLE SQUARE.

Application filed May 8, 1925. Serial No. 28,882.

My invention relates to improvements in foldable squares, and it consists in the combinations, constructions, and arrangements herein described and claimed.

5 An object of my invention is to provide a foldable square of the type employed by carpenters and mechanics which when folded occupies no greater space than one leg of the square as it appears when unfolded.

10 A further object of my invention is to provide a foldable square of the character described in which the legs of the square are rigidly locked against movement relative to one another when in extended position ready

15 for use.

A further object of my invention is to provide a foldable square of the character described in which means is provided for locking the device against unintentional extension or unfolding when the legs are folded.

20 A further object of my invention is to provide a foldable square of the character described which is simple in construction, durable and thoroughly practical for the purposes intended.

25 Other objects and advantages will appear in the following specification, and the novel features of the invention will be particularly pointed out in the appended claims.

30 My invention is illustrated in the accompanying drawings, forming part of this application, in which—

Figure 1 is a front elevation of an embodiment of my invention in an inoperative position,

Figure 2 is a front elevation of the device illustrated in Figure 1 in an operative position.

40 Figure 3 is an elevation of the device illustrated in Figures 1 and 2 partially folded, and

Figure 4 is a sectional view substantially along the line 4—4 of Figure 2.

45 In carrying out my invention I make use of a body member 1 forming one leg of the square. The body member 1 has a portion 2 thereof which extends a part of the length of the body member and which is pivotally secured by means of a rivet 3 to the major part of the body member. This major portion of the body member 1 consists in a rear plate 4, an intermediate or spacing plate 5, and a front plate 6 which are secured to one another. A portion of the spacing plate 5 is cut away leaving a space shown at 7 in

which the second leg 8 of the square is adapted for disposition when out of use. This leg 8 is pivotally mounted upon the rivet 3. The spacing plate 5, as reference to Figure 3 will show, extends from the bottom of the body member to the top 10 of the body member and across the top. The leg 8 is narrower than the leg formed by the body member 1 so that it may be entirely received between the plates 4 and 6 and 2 as shown in Figure 3.

Means for locking the member 2 against movement relative to the body member when the square is folded or when the leg 8 is extended into an operative position as shown in Figure 2, is provided in a locking bolt 11 which is slidably mounted upon the plate 6 and which is adapted to engage with a recess 12 provided in the lower end of the member 2. With reference to Figure 4, it will be noted that the lower edge of the member 2 is arcuate and is beveled slightly as shown at 13. The adjacent edge of the plate 6 is also arcuate to conform with the lower edge of the member 2 and is beveled so that lateral movement of the member is impossible when the member 2 is in the position shown in Figures 1 or 2. The curvature of the lower edge of the member 2 is determined by a radius having its center at the axis of the rivet 3.

With reference to Figure 2, it will be noted that that portion of the leg 8 which encompasses the rivet 3 is substantially annular and is connected with the major portion of the leg 8 by a reduced neck portion 16.

An inwardly extending pin 17 is carried by the member 2 and extends nearly to the adjacent surface of the plate 4. This pin 17 is adapted to engage with either edge of the neck portion 16 of the leg 8. The adjacent edges of the spacing plate 5 are cut away so as to permit rotation of the member 2 about the rivet 3 as an axis.

From the foregoing description of the various parts of the device, the operation thereof may be readily understood. When it is desired to employ the square as a mere rule or straight edge, it is used in its folded position, see Figure 1, and the contiguous surfaces of the member 2 and plate 6 forming parts of the body member are provided with continuous scale markings 18.

At this time the locking bolt 11 is in the position shown in Figure 1 so as to prevent

the member 2 from becoming dislodged or moving relative to the remainder of the body portion.

When it is desired to use the leg 8 in co-operation with the body member 1 or complementary leg, the bolt 11 is moved downwardly out of engagement with the recess 12 of the member 2. The member 2 is then rotated in a counter-clockwise direction whereupon the pin 17 will engage with the left edge of the neck 16 of the leg 8. At this time the leg 8 is in the position shown in Figure 3. This will cause the leg 8 to move in the direction indicated in dotted lines in Figure 2. At this time the edge 19 is exactly perpendicular to the edge 20 of the member 2.

The member 2 is continuously rotated in a counter-clockwise direction until the leg 8 assumes the position shown in Figure 2. At this time the recess 12 will be in registration with the locking bolt 11 and the bolt is pushed upwardly so as to securely lock the member 2 against further movement. The leg 8 is prevented from further rotation in a counter-clockwise direction by abutment of an adjacent portion thereof with a stopping surface 22 provided at the upper righthand edge of the spacing plate 5. The device is now ready for use as a square.

The device is unfolded and restored to the position shown in Figure 1 by unfastening the bolt 11 and rotating the member 2 in a clockwise direction until the recess 12 is again in registration with the bolt.

I claim:

1. A foldable square of the character described comprising a pair of leg portions, one being larger than the other, said leg portions being pivotally connected with one another the larger of said leg portions consisting of two members with an intervening plate to form a slot therebetween, the

smaller being entirely received within the slot in the larger leg portion when the square is folded, a plate forming a part of the larger leg portion for moving the smaller leg portion into a position at 90° with the larger leg portion, said plate being pivotally mounted on the pivotal connection of said legs said plate being provided with a pin adapted to engage with a portion of the smaller leg member when the plate is rotated on the pivotal center of the legs, and a stop member forming a part of the larger leg member adapted to engage with a portion of the smaller leg member when the member is moved 90°.

2. A foldable square of the character described comprising a pair of leg portions; one being larger than the other, said leg portions being pivotally connected with one another, the larger of said leg portions consisting of two members with an intervening plate to form a slot therebetween, the smaller being entirely received within the slot in the larger leg portion when the square is folded, a plate forming a part of the larger leg portion for moving the smaller leg portion into a position at 90° from the larger leg portion, said plate being pivotally mounted on the pivotal connection of said legs said plate being provided with a pin adapted to engage with a portion of the smaller leg member when the plate is rotated on the pivotal center of the legs, a stop member forming a part of the larger leg member adapted to engage with a portion of the smaller leg member when the member is moved 90°, and a locking bolt slidably disposed on the larger leg adapted to move into engagement with the plate, said plate having its outer surface and edges contiguous with the outer surface and edges of the major portion of the larger leg.

JAMES ALISON McWILLIAMS.
